DESIGN FOR A COMBINED CHAIR AND STEPLADDER

Leonard Sunquist, Santa Monica, and Minor
Blythe, Los Angeles, Calif.

Application January 17, 1938, Serial No. 74,369

Term of patent 14 years

To all whom it may concern:

Be it known that we, Leonard Sunquist and Minor Blythe, citizens of the United States, residing, respectively, at 1201 Arizona Street, in the city of Santa Monica, in the county of Los Angeles and State of California, and at 2712 West Vernon Ave., in the city of Los Angeles, in the county of Los Angeles and State of California, have invented a new, original, and ornamental Design for a Combined Chair and Stepladder, of which the following is a specification, reference being had to the accompanying drawing, forming part thereof.

Figure 1 is a rear perspective view of the com-

bined chair and stepladder as it appears when used as a stepladder, with the supporting member in the open position and the chair back member inverted with reference to the chair back position shown in Figure 2; and

Figure 2 is a front perspective view of the combined chair and stepladder as it appears when used as a chair.

We claim:

The ornamental design for a combined chair and stepladder, as shown and described.

LEONARD SUNQUIST.
MINOR BLYTHE.
